CLAIM

The ornamental design for a telephone base, as shown and described.

DESCRIPTION

FIG. 1 is a top isometric view of a telephone base showing my new design;

FIG. 2 is a top elevational view thereof;

FIG. 3 is an underside elevational view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is a top isometric view of a second embodiment of that shown in FIG. 1, the differences therebetween being all encompassed in this view.

FIG. 1

FIG. 2

FIG. 3

FIG. 4

FIG. 5

FIG. 6

FIG. 7

FIG. 8
